UNITED STATES PATENT OFFICE

BENJAMIN F. STRICKLER, OF PEORIA, ILLINOIS.

IMPROVEMENT IN IRONING-BOARDS.

Specification forming part of Letters Patent No. **152,777**, dated July 7, 1874; application filed April 13, 1874.

To all whom it may concern:

Be it known that I, BENJAMIN F. STRICKLER, of the city of Peoria, in the county of Peoria and in the State of Illinois, have invented an Improvement in Ironing-Boards; and do hereby declare that the following is a full, clear, and exact description thereof, reference being had to the annexed drawings making a part of this specification, in which like letters of reference refer to like parts, and in which—

Figure 1 represents a longitudinal elevation of the ironing-board as clamped to a table; Fig. 2, view of the under surface of the board with the legs drawn out; Fig. 3, perspective view of the turn-table with part of the board broken away to exhibit the former.

This invention consists in pivoting the ironing-board upon an attached turn-table beneath the board, by which it is attached or clamped to the edge of a table or other support.

One of the forms in which I construct this invention is as follows, and as illustrated by the drawings, where—

A represents a table; B, the ironing-board, provided with a metal turn-table, *a*, pivoted flat upon the under surface of the same by a pin, *b*, and having two screw-clamps, *d d*, projecting at right angles downward from one edge, and by which the whole is attached to a table. Opposite these, at the other side of said turn-table, are two standards, or short legs, *e e*, of

the same length as, and parallel with, the base stems of the clamps *d d*. On the end of the board is a third clamp, *f*, used to confine the same to the turn-table after the latter is set in the required position for ironing.

The operation of this ironing-board is apparent. The board B is attached to the edge of a table; A, or other convenient place, by placing the feet of the short standards or legs *e e* upon the surface of same, bringing, at the same time, the clamps *d d* up, so as to embrace the edge of the table and tightening the screws. The board can now be swung round to any desired position.

What I claim as my invention is—

1. The combination, with the ironing-board B provided with pivot *b* and clamp *f*, of the turn-table *a*, provided with the standards *e e* and clamps *d d*, as and for the purposes specified.
2. The ironing-board B and turn-table *a*, constructed as described, and provided with the standards *e e* and clamps *d d*, in combination with the table A, as and for the purposes specified.

In testimony that I claim the foregoing ironing-board I have hereunto set my hand this 4th day of April, 1874.

BENJAMIN F. STRICKLER.
